(57) **CLAIM**

The ornamental design for a security monitoring system, as shown and described.

DESCRIPTION

FIG. 1 is a front perspective view of a security monitoring system showing the new design.

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines object portions of the security monitoring system in which the design is embodied that form no part of the claimed design.

1 Claim, 4 Drawing Sheets**FIG. 1**

FIG. 2**FIG. 3**

FIG. 4**FIG. 5**

FIG. 6**FIG. 7**
